UNITED STATES PATENT OFFICE

HOWARD E. BLOOD, OF DETROIT, MICHIGAN, ASSIGNOR TO NORGE CORPORATION, OF DETROIT, MICHIGAN, A CORPORATION OF MICHIGAN

DESIGN FOR A CABINET LEG OR SIMILAR ARTICLE

Application filed January 21, 1931. Serial No. 38,409. Term of patent 14 years.

To all whom it may concern:

Be it known that I, HOWARD E. BLOOD, a citizen of the United States, and a resident of the city of Detroit, in the county of Wayne and State of Michigan, have invented a new, original, and ornamental Design for a Cabinet Leg or Similar Article, of which the following is the specification, reference being had to the accompanying drawing, forming a part thereof.

On the drawing:

The figure illustrates a perspective view of the cabinet leg, or similar article, showing my new design.

I claim as my invention:

The ornamental design for a cabinet leg, or similar article, as shown.

HOWARD E. BLOOD.
